UNITED STATES PATENT OFFICE.

LOUIS MESSEUR, OF NEW YORK, N. Y., ASSIGNOR TO ZINN & MESSEUR, OF SAME PLACE.

COIN-TRAP FOR TOY SAFES, &c.

SPECIFICATION forming part of Letters Patent No. 248,487, dated October 18, 1881.

Application filed September 7, 1881. (No model.)

To all whom it may concern:

Be it known that I, LOUIS MESSEUR, a citizen of the United States, residing at New York, in the county and State of New York, have invented new and useful Improvements in Coin-
5 Traps for Toy Safes and other Articles of a Similar Nature, of which the following is a specification.

This invention consists in a coin-trap for toy
10 safes, pocket-books, or other articles, consisting
of a metal plate, a slot in said plate, a valve
overlapping one of the edges of the slot, and a
spring (one or more) acting on the valve, so
that by the action of the spring or springs the
15 valve is closed, and that when a coin is pressed
down the valve recedes, and as soon as the
coin has passed through the valve closes and
the coin is prevented from passing back.

This invention is illustrated in the accompanying drawings, in which Figure 1 represents
20 a toy safe provided with my coin-trap. Fig. 2 is a plan or top view of the coin-trap detached.
Fig. 3 is an inverted plan of the same, partly
in section. Fig. 4 is a longitudinal section in
25 the plane $x x$, Fig. 3. Fig. 5 is an inverted
plan, partly in section. Fig. 6 is a transverse
section in the plane $y y$, Fig. 1.

Similar letters indicate corresponding parts.

In the example shown in the drawings, the
30 letter A designates a metal plate, which is provided
with a slot, a , and with two lugs, $b b$, one at each end of the slot a . These lugs are, by preference, formed in one piece with the plate
A, by punching the slot a with tongues at its
35 ends, which are afterward bent down to form
the lugs. With the plate A are combined the
valves B B, which are formed of strips of sheet
metal bent, as shown in Fig. 6, and applied to
the opposite edges of the slot a , so as to overlap
40 said edges and to be capable of moving toward
and from each other. Said valves are subjected
to the action of wire springs $c c$, which are retained
by the lugs $b b$, and the ends of which act upon
the valves, as shown in Figs. 3 and 5. The inner edges of the valves B B are rounded off, as shown in Fig. 6, and by the action
45 of the springs $c c$ the valves are forced toward
each other, so that they close the slot a .

When a coin is pressed down between the rounded edges of the valves said valves are forced open against the action of their springs, and after the coin has passed clear through between said valves the valves close and the coin is prevented from passing back.

If desired, my coin-trap may be constructed with a single valve applied to one edge of the slot a , and subjected to the action of a spring or springs which force the same up against the opposite edge of the slot.

When my coin-trap is applied to a toy safe, C, in the manner shown in Fig. 1 the coins which have been passed through the trap into the safe cannot be removed through the coin-receiving opening of the safe, and they can only be reached by opening the cover D.

In order to give to the plate A a good hold on the cover D of the safe, a secondary plate may be placed on the inside of the cover and fastened thereto by the same rivets which serve to fasten the plate A, said inner plate being made of precisely the same size as the outer plate, and provided with slots large enough to permit the valves B B to open and close freely.

What I claim as new, and desire to secure by Letters Patent, is—

1. A coin-trap for toy safes and other similar articles, consisting of a metal plate, a slot in said plate, a valve overlapping one of the edges of the slot, and a spring (one or more) acting on the valve, substantially as and for the purpose set forth.

2. A coin-trap for toy safes and other similar articles, consisting of a metal plate, a slot in said plate, two lugs, one at each end of the slot, two valves overlapping the edges of the slot, and two springs retained in position by the lugs and acting on the valves, substantially as and for the purpose specified.

In testimony whereof I have hereunto set my hand and seal in the presence of two subscribing witnesses.

LOUIS MESSEUR. [L. S.]
